No. 653,803.

Patented July 17, 1900.

H. HARDEN.
SHAFT SUPPORT.

(Application filed Apr. 14, 1900.)

(No Model.)

FIG. 1.

UNITED STATES PATENT OFFICE.

HARRY HARDEN, OF LONDON, OHIO, ASSIGNOR OF ONE-HALF TO JOHN CARTER AND MISSOURI CARTER, OF SAME PLACE.

SHAFT-SUPPORT.

SPECIFICATION forming part of Letters Patent No. 653,803, dated July 17, 1900.

Application filed April 14, 1900. Serial No. 12,879. (No model.)

To all whom it may concern:

Be it known that I, HARRY HARDEN, a citizen of the United States, residing at London, in the county of Madison and State of Ohio, 5 have invented a new and useful Shaft-Supporter, of which the following is a specification.

This invention relates to thill-supports, and has for its object to provide an improved device of this character which is designed to support the thill in its operative position and also when elevated and out of use. It is furthermore designed to provide a support which may be applied to any of the common or ordinary forms of thills without changing or altering the latter and also to have the device adjustable to fit different thills and to support the latter at different inclinations.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a side elevation of a vehicle-thill supported in its operative position by means of the present invention. Fig. 2 is a sectional elevation thereof in the elevated position of the thill. Fig. 3 is a top plan view of Fig. 1.

Corresponding parts in the several figures of the drawings are designated by like characters of reference.

Referring to the drawings, 1 designates an axle, and 2 a thill, which is connected to the axle by means of any suitable form of thill-coupling, herein shown as an axle-clip 3, having the opposite bearing-ears 4, between which is pivoted the thill-iron 5 by means of the thill-bolt 6. It will be understood that these parts may have any preferred form and are shown in the drawings to more adequately illustrate the application and operation of the present support.

In carrying out the present invention there

is provided a substantially L-shaped arm 7, which has its upright member located in rear of the axle, and its horizontal member is provided with perforations to receive the opposite arms of the axle-clip, so that it may be 55 secured flat against the under side of the axle and take the place of the usual plate that connects the arms of the clip. The upper end of the L-shaped arm is bifurcated to form a fork 8, within which is pivoted a link 9, 60 that is designed to swing to the opposite front and rear sides of the arm, and is provided at its outer free end with a bifurcation to form a fork 10.

Between the outer free end of the link 9 and the thill there is a longitudinally-adjustable link, comprising a nipple or sleeve 11, having its outer end pivoted within the forked end of the link 9 and its opposite end provided with a screw-threaded socket 12 for the 70 reception of one end of a screw-threaded pin or rod 13. At the opposite end of the pin or rod there is another nipple or sleeve 14, that has its outer end provided with a screw-threaded socket 15 for the reception of the 75 adjacent end of the pin 13, and the inner end of this sleeve is pivoted between the opposite bearing-ears 16, formed on the plate 17, which is secured to the upper or rear side of the thill. The pin or rod 13 is provided at its 80 middle with an eye or perforation 18 or other means whereby the pin may be turned, and it will be understood that the opposite ends of the pin are oppositely screw-threaded, so as to form a turnbuckle for adjusting the 85 length of the link between the thill and the link 9.

Bearing upon the pivotal connection between the sleeve 14 and the plate 17 is a substantially L-shaped spring 18, which has its 90 upright member secured flat against the plate 17 and above the bearing-ears 16 by means of an intermediate fastening 19, which also serves to secure the plate to the thill. At the upper end of the plate there are provided the opposite lugs or ears 20 to bear against the opposite edges of the spring and hold the latter in place. It will be observed that the tongue or free outwardly-projecting portion of the spring bears against the upper side of 95 100

the joint between the adjustable link and the thill, so as to prevent accidental breaking of this joint or looseness thereof.

In the normal operative position of the thill, 5 as shown in Fig. 1, the links are extended in alinement transversely across the axle, so as to support the outer ends of the thill above the ground or floor and at the same time permits of the slight vertical movement due to 10 the movement of the animal. When the thill is thrown upwardly and out of the way when not in use, as shown in Fig. 2, the joint between the two links breaks upwardly and the link 9 swings to the rear side of the L-shaped 15 support 7 until the centers of the joints at the opposite ends of the link are in alinement, so as to lock the thill in this position. It will now be understood that the spring 18 is designed to place a tension upon the linked 20 connection between the axle and the thill, so that a decided effort must be made to swing the thill from one position to the other, and thus accidental breaking of the joints is effectually prevented. Also the linked connection 25 is longitudinally adjustable, so as to accommodate the device to different vehicles and also to support the thills at different inclinations, as may be convenient or necessary in any particular case. Moreover, the support 30 may be applied to any common or ordinary form of thill without changing or altering the same and without in any manner interfering with the usual operation thereof.

What is claimed is—

35 1. In a thill-support, the combination with an axle, and a thill, of a support, which is pivotally connected at opposite ends to the axle and the thill respectively, and comprises pivotally-jointed links, and a substantially 40 L-shaped spring secured to the thill and bearing against the pivotal connection between the latter and the support, to prevent accidental breaking of the connection.

2. In a thill-support, the combination with an axle, and a thill, of opposite sleeves, which 45 are pivotally connected to the axle and the thill, respectively, and also are provided with oppositely-disposed internal screw-threads, and a pin or rod, having its respective ends oppositely screw-threaded and fitting the respective sleeves, to adjust the length of the connection between the axle and the thill,

3. In a thill-support, the combination with an axle, and a thill, of a support, comprising a link pivoted to the axle and arranged to 55 swing transversely across the upper side and to the front and rear sides thereof, and a second link, having one end pivoted to the free end of the first-mentioned link, and its opposite end pivotally connected to the upper side 60 of the thill, both links being extended in longitudinal alinement transversely across the axle, in the normal operative position of the thill, and folded longitudinally upon each other in rear of the axle, in the elevated position of the thill.

4. A thill-support, comprising a substantially L-shaped arm for connection with an axle, and having its upper end forked, a link having one end pivoted in the fork of the arm, 70 and its opposite end provided with a fork, an internally-screw-threaded sleeve having its outer end pivoted within the fork of the link, a turn-screw having one end fitted in the sleeve, an internally-screw-threaded sleeve 75 fitted to the opposite end of the turn-screw, and an attaching-plate for application to a thill, and also having a pivotal connection with the outer end of the latter sleeve.

In testimony that I claim the foregoing as 80 my own I have hereto affixed my signature in the presence of two witnesses.

HARRY HARDEN.

Witnesses:

B. P. JONES,
J. F. KIRKPATRICK.
